UNITED STATES PATENT OFFICE.

FRANK N. SPEAR, OF LOS ANGELES, CALIFORNIA.

FUEL-FEEDER FOR FURNACES.

SPECIFICATION forming part of Letters Patent No. 789,677, dated May 9, 1905.

Application filed September 12, 1901. Serial No. 75,138.

To all whom it may concern:

Be it known that I, FRANK N. SPEAR, a citizen of the United States, residing at Los Angeles, in the county of Los Angeles and 5 State of California, have invented an Improvement in Fuel-Feeders for Furnaces, of which the following description, in connection with the accompanying drawings, is a specification, like letters on the drawings representing like parts.

My invention has for its object to improve apparatus for feeding fine or pulverized coal or fuel to furnaces for steam-boilers and the like, my invention relating to apparatus of 15 the general type shown and described in Letters Patent of the United States issued to me under date of August 7, 1900, No. 655,464.

In order that my invention may be understood, I will first disclose the same in connection with one form of apparatus made in accordance therewith.

Referring to the drawings, Figure 1 in vertical section, partial elevation, illustrates one form of apparatus made in accordance 25 with my invention; Fig. 2, a left-hand or front elevation of the delivering apparatus shown in Fig. 1, the automatic appliances being omitted in this figure for the sake of clearness; and Fig. 3, an enlarged sectional 30 detail of the end of the delivery device.

In the particular embodiment of my invention selected for illustration herein and shown in the drawings, A is a fuel-supply chamber that may be the end of a conduit or chute 35 leading from a hopper or coal-supplying device, or it may be hopper-shaped, as here shown, to receive directly thereto the fuel from the bins, cars, or other source of supply.

Within the supply-chamber A, and preferably near the bottom thereof, is arranged a 40 rotary feeding and loosening device a, shown as composed of a shaft a', surrounded by a tubular casing or barrel a'', perforated to receive a plurality of feeding and loosening 45 members or pins a''. These pins, as shown, are cut of uniform length and are driven through the openings of the shell or barrel a'' until they contact with the shaft a', thus insuring uniform projection of the said pins.

For the best results these pins are staggered 50 throughout the length of the device.

In the bottom of the supply-chamber A is an opening or communication a⁴, that opens into the delivery-chamber b, formed in a suitably shaped and constructed casting, as here 55 shown or otherwise, as desired. This casting is secured to or mounted in front of the end wall of the furnace and communicates with the interior thereof, so that fuel received into said chamber may be delivered therefrom directly into the combustion-chamber of the furnace. For this purpose there is arranged in the said delivery-chamber a delivery device C, shown as rotary. This delivery device as here constructed is in the 60 form of a cylinder or barrel c, mounted at its ends upon suitable journals and provided at its periphery with a series of longitudinal vanes or wings c', which during rotation of the device project the fuel contained in the said 65 supply-chamber into the combustion-chamber to be consumed therein. In the present construction the vanes or wings c' of the delivery device are shown as made of comparatively thin sheets of metal folded along their 70 middle lines and inserted in longitudinally-arranged grooves in the cylinder or barrel c, they being confined in said grooves by locking-strips c'', driven thereinto and held frictionally or otherwise, as desired. In the 75 present construction the said locking-strips (see Fig. 3) are prolonged beyond the ends of the vanes or wings c' and are secured by rings c³, that encircle the ends thereof.

The communication a⁴ between the supply-chamber A and the delivery-chamber b has a movable wall, herein shown as formed by a roller d, journaled in suitable bearings in the side walls of the delivery-chamber. Opposed to this movable wall d is a controlling device e, shown in the form of a gate carried by a support fulcrumed at e', the said gate or controlling device having a movement toward and from the movable wall of said communication a⁴ for the purpose of 85 regulating the area of the said communication and the resultant quantity of material 90 permitted to pass therethrough from the sup-

ply-chamber to the delivery-chamber. For moving this controlling device I have here provided a hand-wheel e^2 upon the end of a shaft e^3 , having a threaded portion e^4 tapped 5 into the front wall of the supply-chamber, with its end extended through an opening in the support for said controlling device and provided at opposite sides thereof with washers or lugs e^5 e^6 , whereby in-and-out movement of the said shaft, due to rotation thereof by said hand-wheel, operates to move the said controlling device about its said fulcrum to open and close, more or less, the said passage or communication a^4 .

15 In practice the feed and clearing device a and the delivery device C may be rotated in any suitable or desired manner; but for convenience one may be rotated from the other by suitable worm or gearing, as shown in Fig. 2, and wherein a worm-wheel f on one of the journals of the feeding and clearing device meshes with a worm f' , that carries a beveled pinion f^2 , meshing with a beveled pinion f^3 on the journal of the delivery device C , the latter having a suitable driving-pulley f^4 , which may be belted to any convenient counter-shaft or motor for driving. I prefer also to rotate the roller d at a slow rate of speed in order to avoid possible clogging of the material in the communication a^4 between the two chambers, and this may conveniently be done by belting it, as by a belt g , to a pulley on the journal of the feeding and clearing device a (see Fig. 2) or otherwise, at the convenience of the operator. I also provide said roller d with a hand-wheel g' , by which said roller may be rotated to cause movement of the movable wall here formed by said roller manually and independently of any other driving means which may be employed. In fact, the manual operation of said roller or wall may alone be depended upon, if desired.

The operation of the apparatus is as follows, viz: Fuel of the desired degree of fineness, such as dust-coal, is deposited in the supply-chamber A and is kept constantly loosened near the bottom of said chamber by the rotary device a , which also acts as a 45 feeder to furnish constant feed or flow of the material to the controlled communication a^4 , leading to the delivery-chamber. The amount of material permitted to pass to the delivery-chamber is determined by the controlling device or gate e , and clogging of the material in the communication a^4 is guarded 50 against and prevented by the movable wall here formed by the roller d . The material received into the delivery-chamber b is 55 caught by the rapidly-revolving delivery device C and is projected into the combustion-chamber of the furnace in such a manner as to ignite readily therein and burn in a manner well understood by those conversant 60 with the art. Air in suitable quantities is

admitted to the delivery-chamber through an opening h in the upper portion thereof and an opening h' below the said chamber, one or both of which may, if desired, be controlled or adjusted as to area in any suitable 70 or desired manner. (Not herein shown.) The air thus admitted to the delivery-chamber is mixed with the fuel by the action of the delivery device rotating therein, so as to provide the most efficient mixture of fuel and air for the best combustion and highest efficiency within the combustion-chamber. 75

The apparatus as here described may be successfully operated, depending alone upon manual adjustment and control of the various parts; but for convenience automatic means may be employed for the purpose, and I have here shown one form of automatic control which I will now describe.

M is a pressure-responsive device of any 85 suitable or desired construction (here shown as a cylinder m) in communication by a pipe m' with the boiler, whereby boiler-pressure is admitted to said cylinder, where it acts upon a piston m^2 , opposed by a spring m^3 , and moves said piston along more or less within its said cylinder, according to the pressure within the boiler. The piston m^2 has a piston-rod m^4 connected at its upper end in suitable manner with a vibrating lever m^5 , 90 fulcrumed at m^6 . This lever at its opposite ends is connected by cords or other flexible connections m^7 m^8 with a drum m^9 , fast on the shaft e^3 , that controls the position of the controlling device or gate e , one of the said 95 cords being wound about and upon said drum in one direction and the other cord in an opposite direction. As the steam-pressure within the boiler rises it will act to move the piston m^2 forward within its cylinder m , and thereby rock the lever m^5 in a direction to rotate said shaft e^3 to move said gate e to close more or less the passage or communication a^4 . This reduces the amount 100 of fuel permitted to pass to the delivery device, and consequently reduces the heating effect within the combustion-chamber. As the pressure within the boiler falls the piston m^2 will be returned within its said cylinder 105 by the spring m^3 , causing opposite movement of the said lever m^5 and opposite rotation of said shaft e^3 , thereby to open more or less the said passage a^4 and increase the amount of fuel delivered to the combustion-chamber, and consequently increase the resultant heating effect within said combustion-chamber. Thus the apparatus may be 110 strictly automatic, and because of the nature of the fuel used and the efficiency of the apparatus disclosed close regulation may at all 115 times be had.

The roller d , which forms the movable wall for the controlled passage a^4 in the construction here shown, may be said to constitute one form of clearing device, because by its 120

rotation at any time it operates as a clearer to free the said passage ^{a4}.

For most efficient operation the fuel particles should be delivered to the combustion-chamber in an individualized or separated condition surrounded each by an atmosphere or film of oxygen. Owing to the tendency of the pulverulent fuel to pack or agglomerate wherever the fuel particles are allowed to accumulate or come together in masses, this result is ordinarily difficult to attain, the tendency being for the associated masses to adhere in their passage to and after entrance into the combustion-chamber.

15 In the embodiment of my invention herein described, however, the fuel which is assembled in mass in the hopper is agitated and freed in the most effective position at or about the entrance to the passage leading to the delivery-chamber, so that the same starts on its passage in an individualized condition, in which condition, too, and therefore through the coöperation of the agitator, the movable clearing-wall is best fitted to act upon the fuel to assist its passage into the delivery-chamber. It is also to be observed that the location of the delivering device relatively to the fuel-passage and the movable wall is such that the fuel is received by the former immediately on its entrance into the delivery-chamber while still in motion and without opportunity to accumulate or pack and immediately upon entrance delivered to the combustion-chamber at a uniform rate

35 and in the most efficient condition for combustion. It is to be further observed that the automatic control of the rate of fuel delivery is such that it does not lead to the agglomeration of any of the fuel particles in transit.

While I have here disclosed one embodiment of my invention, said invention is not limited to the embodiment disclosed, for it may be varied within the spirit and scope of the invention.

Having described my invention and without limiting myself as to details, what I claim, and desire to secure by Letters Patent, is—

50 1. In a pulverulent-fuel-feeding device, feeding means for feeding the fuel to the combustion-chamber comprising a fuel-supply chamber, a delivery-chamber communicating therewith through an open gravity-fed passage to provide an open uninterrupted communication between the delivery and fuel-supply chambers, a movable clearing-wall for said passage to maintain and assist the constant supply of fuel therethrough, and agitating means coöperating with and in close proximity to said movable wall and said passage to prevent the agglomeration of the fuel particles near the latter and to permit the effective action upon the same by the

65 said movable wall.

2. In a pulverulent-fuel-feeding device, feeding means for feeding the fuel to the combustion-chamber comprising a fuel-supply chamber, a delivery-chamber communicating therewith through an open supply-passage to provide uninterrupted communication between the delivery and fuel-supply chambers, agitating means to maintain the separation and prevent the agglomeration of the fuel particles at the supply-passage, a movable clearing-wall for said passage to assist the movement of the separated fuel particles therethrough and mechanical delivery means for receiving the fuel directly from said passage and movable wall in its separated condition and delivering the same to the combustion-chamber also in a separated or individualized condition.

3. In a pulverulent-fuel-feeding device, fuel-feeding means for feeding the fuel to the combustion-chamber comprising a fuel-supply chamber, a delivery-chamber communicating therewith through a supply-passage adapted to restrict and measure the fuel passing therethrough, a movable clearing-wall for said passage to assist the movement of the fuel therethrough, agitating means in close proximity to said supply-passage to maintain the separation of the individual fuel particles thereat, and mechanical delivery means to receive the fuel particles in their individualized condition on their emergence from the supply-passage and to deliver the same into the combustion-chamber.

4. In a pulverulent-fuel-feeding device, feeding means for feeding fuel to the combustion-chamber comprising a fuel-supply chamber, a delivery-chamber communicating therewith through a supply-passage adapted to restrict and measure the amount of fuel passing therethrough, means for varying the area of said passage to control the flow of fuel therethrough, a movable clearing-wall for said passage to assist the movement of fuel therethrough, and agitating means coöperating with and in close proximity to said movable wall and said passage to separate or individualize the fuel particles passing therethrough and permit effective action of the movable wall upon the separated fuel particles.

5. In a pulverulent-fuel-feeding device, fuel-feeding means for feeding fuel to the combustion-chamber comprising a fuel-supply chamber, a delivery-chamber communicating therewith through an open uninterrupted supply-passage to provide an open uninterrupted communication between the delivery and fuel-supply chambers, a movable clearing-wall for said passage to assist and maintain the constant supply of fuel therethrough, delivery means within said delivery-chamber to receive the fuel particles from the said passage and movable wall in their individualized or separated condition and to deliver them in such condition to the

combustion-chamber, and means for varying the area of the supply-passage to control the flow of fuel therethrough.

6. In a pulverulent-fuel-feeding device, feeding means for feeding the fuel to the combustion-chamber comprising a supply-chamber, a delivery-chamber, a supply-passage between the two, mechanical means within said delivery-chamber to receive the fuel from said passage and deliver the same in an individualized or separated dust-like condition to the combustion-chamber, and means responsive to changes in boiler conditions for controlling the area of the supply-passage.

7. In a pulverulent-fuel-feeding device, feeding means for feeding the fuel to the combustion-chamber comprising a supply-chamber, a delivery-chamber, an open supply-passage to provide an open uninterrupted communication between the delivery and fuel-supply chambers and permit the passage of the pulverulent fuel therethrough in an individualized state, delivery means within the chamber to receive the fuel as it emerges from the supply-passage in its individualized or separated condition and to maintain and deliver it in like condition to the combustion-chamber, and means responsive to changes in boiler conditions for controlling the flow of the separated fuel particles therethrough.

8. In a pulverulent-fuel-feeding device, feeding means for feeding fuel to the combustion-chamber comprising a fuel-supply chamber, a delivery - chamber communicating therewith through a supply-passage, agitating means in proximity to said passage, a movable wall for said passage, and delivery means in said delivery-chamber, said agitating means, movable wall and delivery means coöperating with said supply - passage to

maintain the movement of the pulverulent fuel throughout its course from the supply-chamber to the combustion - chamber in an individualized or separated condition of the fuel particles.

9. In a pulverulent-fuel-feeding device, feeding means for feeding the fuel to the combustion-chamber comprising a fuel-supply chamber, a delivery-chamber communicating therewith through an open supply-passage to provide an uninterrupted communication between the delivery and fuel-supply chambers, a movable clearing-wall for said passage to maintain and assist the constant supply of fuel therethrough, and delivery means to receive the fuel particles on emergence from the said passage and while in their individualized condition and to deliver the same into the combustion-chamber in like condition.

10. In a pulverulent-fuel-feeding apparatus a supply-chamber provided with a feeding and loosening device comprising a shaft, a barrel surrounding the same but having an annular space between said shaft and barrel, and loosening and feeding pins inserted through the barrel against said shaft, as described.

11. In a pulverulent-fuel-feeding apparatus a supply-chamber provided with a feeding and loosening device comprising a shaft, a surrounding barrel, and loosening and feeding pins inserted exteriorly through the latter against said shaft, as described.

In testimony whereof I have signed my name to this specification in the presence of two subscribing witnesses.

FRANK N. SPEAR.
